M. SWINTEK

CENTRIFUGAL DREDGING PUMP

Filed April 17, 1922

Inventor
MARTIN SWINTEK

By Earl M. Sinclair
Atty.

UNITED STATES PATENT OFFICE.

MARTIN SWINTEK, OF EDDYVILLE, IOWA.

CENTRIFUGAL DREDGING PUMP.

Application filed April 17, 1922. Serial No. 554,135.

To all whom it may concern:

Be it known that I, MARTIN SWINTEK, a citizen of the United States of America, and resident of Eddyville, Wapello County, 5 Iowa, have invented a new and useful Centrifugal Dredging Pump, of which the following is a specification.

The object of this invention is to provide an improved construction for a centrifugal 10 pump especially adapted for dredging and similar purposes.

A further object of this invention is to provide an improved centrifugal dredging pump in which means is provided to overcome and counteract the tendency of sand and other substance pumped to be discharged laterally at the circumference of the 15 rotor, thereby causing clogging and excessive wear between the rotor and shell.

20 A further object of this invention is to provide an improved centrifugal pump for dredging or sand pumping purposes, in which the rotor is provided with auxiliary pumping chambers on opposite sides of the 25 main or sand pumping chamber, said auxiliary pumping chambers inducting streams of clear water to equalize lateral pressure circumferentially of the main pumping chamber.

30 My invention consists in the construction, arrangement and combination of elements hereinafter set forth, pointed out in my claims and illustrated by the accompanying drawing, in which—

35 Figure 1 is a side elevation of a pump embodying my improvements. Figure 2 is a longitudinal vertical section through the pumping chamber and rotor. Figure 3 is a cross-section on the line 3—3 of Figure 2.

40 In the construction of the device as shown the numeral 10 designates a suitable base on which are mounted spaced bearing members 11, 12 in which a shaft 13 is journaled for rotation, said shaft being driven from a 45 suitable source of power by connections to a belt pulley 14 fixed to said shaft between said bearings. The shaft 13 projects outwardly beyond the bearing 12 and through a stuffing box 15 into the pump housing. The

50 pump housing is of generally circular form, concentric with the shaft 13, and is formed with a central or main chamber 16 and with auxiliary chambers 17, 18 on opposite sides of and communicating with said main chamber, said lateral chambers being of less diameter than the central chamber. A rotor is

fixed to and for rotation with the shaft 13 within the pump housing, having at its inner end a hub 19 secured to said shaft. The rotor is also formed with four vertical walls 60 20, 21, 22, 23, formed of annular plates or disks spaced apart. The walls 20, 21 form the sides of the central or main pumping chamber of the rotor which is located within the main pumping chamber 16 of the housing, and are connected transversely at spaced intervals by arcuate vanes 24, in this instance four in number. The wall or partition 20 is formed on or fixed to the hub 19, and the wall or partition 21 is formed at 65 its inner circumference with an outwardly directed annular flange or collar 25, preferably of somewhat greater diameter than said hub 19. The wall 22 is located outside of and spaced from the wall 20, and is connected thereto by arcuate vanes 26; and the wall 23 is located outside of and spaced from the wall 21, and is connected thereto by arcuate vanes 27. The vanes 26, 27 are in 70 this instance four in number and correspond in location and arrangement with the main vanes 24. The central openings of the walls 22, 23 are of greater diameter than those of the intermediate walls or partitions 20, 21, so that said walls 22, 23 are spaced from the 75 hub 19 and flange or collar 25 respectively, and annular inlet openings 28, 29 are provided between said members, leading to the auxiliary pumping chambers of the rotor, enclosed respectively by the walls 20—22 80 85 90 and 21—23, and located within and discharging centrifugally to the auxiliary chambers 17, 18 respectively of the housing. An induction tube or sleeve 30 is provided and is arranged axially of and projecting 95 through the outer side wall of the pump housing, and at its inner end is received within and provides a journal for the collar or flange 25 of the rotor. The induction sleeve or tube 30 is formed at its outer end with a peripheral flange 31 by which it is attached to the flange 32 of an inlet pipe 33, through the medium of bolts 34. The induction sleeve 30 is formed between its ends, and near its outer end, with a peripheral 100 105 flange 35 by means of which it is attached rigidly to a flange 36 of the pump housing, through the medium of bolts 37. The inlet pipe 33 leads to a place from which material is to be removed by suction, as to the bed of a body of water, and is provided with 110 a suitable nozzle (not shown), whereby

water and sand or other material may be drawn into the pump housing. Such material is drawn to the axis of the main pumping chamber of the rotor, the inner ends of 5 the vanes 24 thereof being cut away on lines connecting the central apertures of the walls 21 and 20, and is discharged radially between said vanes to the annular chamber 16 of the housing. An outlet nozzle 38 is provided 10 at the circumference of the central chamber 16 of the housing, which may receive connection of a pipe 39 leading to any suitable place of discharge. Water inlet pipes 40, 41 are provided, each having communication at one end with and near the axis of one of the auxiliary or lateral chambers 17, 18 of the housing, and said pipes may be connected at their opposite ends with a common pipe 42 leading to and beneath 15 the surface of a body of water and adapted to draw water only from such source of supply and deliver it to said chambers, through the action of the vanes 26 and 27 of 20 the auxiliary chambers of the rotor.

25 In practical use the rotor is revolved by the means described and the suction produced by the vanes 24 causes water and sand, for instance, to be drawn from the bed of a river or other body of water, through the 30 pipe 33, sleeve 30 to the axial portion of the main pumping chamber of the rotor and discharged by centrifugal force beyond the outer ends of the vanes to the annular portion of the main chamber 16 of the housing, whence it is led away through the nozzle 38 and pipe 39 to the place provided. It is plain 35 that there must be a clearance between the outer circumferences of the walls or partitions 20, 21 of the rotor and the walls of the 40 pump housing, and in pumping sand with a pump of this type it has been found that there is a considerable tendency to discharge the sand laterally over said walls or partitions, instead of radially into the chamber 45 16. This causes excessive friction and wear between the motor and housing, necessitating frequent replacement or repair of parts, and it is to overcome this tendency and to equalize the lateral pressure, that I have provided 50 the two lateral or auxiliary pumping chambers of the rotor, located on opposite sides of the main pumping chamber. When the rotor is revolved the suction of the vanes 26, 27 causes an influx of water only through the 55 pipe 42 and branches 40, 41, the former pipe leading from a point at or near the surface of the body of water so that no sand is drawn therethrough. This water is drawn 60 in through the axial openings of the outer walls 22, 23 of the rotor to the auxiliary pumping chambers thereof and is discharged by centrifugal force radially by the vanes 26, 27 to circumferential portions of the lateral chambers 17, 18 of the housing. The annular space between the lateral chambers of 65

the rotor and the circumferences of the chambers 17, 18 is small so that considerable force is exerted by the water discharged from the auxiliary pumping chambers, which balances, equalizes and counteracts lateral pressure outwardly from the main pumping chamber and prevents sand from being discharged over the circumferential margins of the walls 20, 21 thereof. This water 70 mingles with the sand and water in the main chamber 16 of the housing, and is led away through the pipes 38, 39. The discharge of water laterally from the auxiliary pumping chambers assists in keeping the chambers clear by enhancing the flotation and consequent free movement of the sand. 75

The combined capacity of the two lateral or auxiliary pumping chambers of the rotor preferably is less than that of the main or sand pumping chamber; and means may be 80 provided if desired, such as valves in the pipes 40, 41, for regulating the flow of water to said auxiliary chambers. 85

I claim as my invention—

1. In a centrifugal pump, a housing 90 formed with a main chamber and a lateral chamber at each side thereof, said main chamber being of greater diameter than said lateral chambers, and a rotor mounted for rotation in said housing, said rotor being formed with a main pumping chamber in the main chamber of said housing, means for drawing material in suspension into said housing and rotor axially of the main pumping chamber, a discharge outlet at the circumference of the main chamber of the housing, said rotor being formed with an auxiliary pumping chamber at each side of 95 said main pumping chamber, separate means for drawing water only into each of said auxiliary pumping chambers and discharging the same into the lateral chambers of said housing, thereby equalizing lateral pressure from said main pumping chamber. 100

2. In a centrifugal pump, a rotor comprising a shaft, spaced annular walls fixed to said shaft and enclosing a main pumping chamber, vanes connecting said annular walls, annular walls outside of and spaced from each of the first mentioned walls and forming therewith lateral auxiliary pumping chambers of less capacity than the first pumping chamber, and vanes in each of said auxiliary pumping chambers, an inlet pipe leading to and axially of the main pumping chamber, and an inlet pipe leading to the central portion of each of the auxiliary pumping chambers. 110

3. In a centrifugal pump, a shaft, a rotor 115 formed with a hub secured to one end of said shaft, a wall fixed to and radiating from said hub, a second wall of annular form spaced from the first wall and forming therewith a main pumping chamber, vanes fixed to and connecting said walls, an inlet 120

125

pipe communicating with the aperture of said annular wall and also forming a journal therefor, annular walls arranged outside of and spaced from the first mentioned walls 5 and forming therewith lateral auxiliary pumping chambers, vanes connecting the outside walls to the main chamber walls, the central apertures of the outside walls being of greater diameter than the hub and inlet 10 pipe respectively whereby annular inlet openings are formed leading to the auxiliary pumping chambers.

4. In a centrifugal pump, a housing formed with a main chamber and lateral 15 chambers at each side of and of less diameter than the main chamber, a driving shaft, a rotor fixed to said shaft and formed with four spaced walls providing three pumping

chambers, an inlet pipe leading to and arranged axially of the central pumping chamber and adapted to deliver material in suspension thereto, such material being discharged centrifugally to the main housing chamber, the outermost walls of the rotor being of annular form, means for supplying 25 water to the lateral chambers of the rotor through the central apertures of its outside walls, which water is discharged centrifugally to the lateral housing chambers and tends to prevent lateral discharge to said lateral 30 chambers of the material in suspension.

Signed at Des Moines, in the county of Polk and State of Iowa, this 24th day of March, 1922.

MARTIN SWINTEK.
